M. E. BIGELOW

WRENCH

Filed Aug. 4, 1927

Merle E. Bigelow, INVENTOR
By Victor J. Evans

ATTORNEY

UNITED STATES PATENT OFFICE.

MERLE E. BIGELOW, OF MILFORD CENTER, OHIO.

WRENCH.

Application filed August 4, 1927. Serial No. 210,638.

This invention relates to a wrench, the general object of the invention being to provide means for operating the wrench by power until the nut becomes tight and then 5 operating the wrench by hand to give the nut its final movements, with means for returning the handle part of the wrench to its starting point by the power means, after it has been moved by hand in giving the nut 10 its final turning movement.

Another object of the invention is to provide clutch means for attaching the power driven member to the actuating member of the wrench.

15 This invention also consists in certain other features of construction and in the combination and arrangement of the several parts, to be hereinafter fully described, illustrated in the accompanying drawings and 20 specifically pointed out in the appended claim.

In describing my invention in detail, reference will be had to the accompanying drawings wherein like characters denote like 25 or corresponding parts throughout the several views, and in which:

Figure 1 is a longitudinal sectional view through the improved wrench.

Figure 2 is a side view.

30 Figure 3 is a section on line 3—3 of Figure 1.

In these views, 1 indicates a casing which is formed with or suitably attached to the hollow handle or stem 2. A shaft 3 is 35 journaled in the hollow stem and has a worm 4 thereon which meshes with the worm teeth on the socket member 5 which is rotatably mounted in the casing and the socket 6 of which is adapted to receive a nut or other 40 part to be turned. The shaft extends a considerable distance from the outer end of the stem or handle and has a head 7 on its outer end which is rotatably mounted in a member 8 which has a square stem 9 for receiving the flexible shaft of the power means. A disk 10 is arranged on the inner face of 45 the member 8 to form one part of the friction clutch. A clutch sleeve 11 is keyed to the shaft 3 and carries a disk 12 for engaging the disk 10.

A hand grip 13 has a threaded socket 14 at one end to receive the threaded outer end of the stem 2 and said hand grip is formed with a chamber 15 to receive the flanged 55 outer end of the sleeve 11. A spring 16 is arranged in the hand grip and encircles the

shaft and bears against a part of the grip and one end of the sleeve 11 and acts to force the sleeve toward the member 8 so as to keep the clutch disks in engagement with 60 each other. The tension of the spring can be adjusted by screwing or unscrewing the hand grip on the stem.

From the foregoing it will be seen that the wrench can be used as an ordinary wrench 65 by seizing the hand grip in the hand and moving the handle about the axis of the casing. In this action, the worm is locked to the socket member 5 and thus the socket member will move with the rest of the 70 wrench. By attaching a flexible power shaft to the stem 9 of the member 8, the shaft 3 will be rotated through means of the clutch parts and thus the worm 4 will rotate the member 5 in the casing 1. With this 75 wrench, a nut or other object can be screwed on or a bolt or the like by the power means acting through the shaft 3 and the worm gearing to rotate the member 5 and thus turn the nut. When the nut becomes tight, 80 and the power means cannot turn it any more, the wrench is then manipulated by the hand as an ordinary wrench to further tighten the nut, and after the handle has been moved to cause the member 5 to give 85 the nut a partial turning movement, the hand is released from the hand grip so that the power means, acting through the clutch parts, will turn the shaft 3 and thus the worm, acting on the teeth of the member 5 90 which is held against movement by the nut, will return the handle and the parts associated therewith, to their original position so that the handle can be again moved by hand to give the nut another tightening 95 movement. This action is kept up until the nut is tight on the bolt. If necessary or desired, the hand grip can be turned at the end of each movement of the handle, first to disengage the clutch parts and then to engage 100 the clutch parts to prevent choking of the motor of the power means and to cause the motor to rotate the shaft 3 to return the handle to its initial position.

It is thought from the foregoing description that the advantages and novel features of my invention will be readily apparent.

I desire it to be understood that I may make changes in the construction and in the combination and arrangement of the several 110 parts, provided that such changes fall within the scope of the appended claim.

What I claim is:—

A wrench of the class described comprising a casing, a hollow handle connected therewith, and having its outer end threaded, a socket member rotatably mounted in the casing and having worm teeth on its periphery, a shaft rotatably mounted in the handle and having a worm thereon engaging the worm teeth, said shaft having its outer end extending beyond the outer end of the handle, a clutch sleeve slidably but non-rotatably connected with the extended end 10 of the shaft, a drive member rotatably con-

nected with the end of the shaft, a clutch disk on the drive member, a clutch disk on the sleeve, a hand grip threadedly engaging the threaded end of the handle and surrounding a portion of the shaft and a part of the clutch sleeve and a spring in the hand grip for applying pressure to the clutch sleeve to force the disks together, said spring having its tension adjusted by the adjustment of the hand grip on the handle. 15 20

In testimony whereof I affix my signature.

MERLE E. BIGELOW.
